(57) **CLAIM**

The ornamental design for a coaxial cable compression tool, as shown and described.

DESCRIPTION

1. Coaxial cable compression tool

1.1 : Front

1.2 : Back

1.3 : Left

1.4 : Right

1.5 : Perspective

1.6 : Perspective

1.7 : Bottom

1.8 : Top

The features shown in broken lines form no part of the claimed design.
